Attorneys.

UNITED STATES PATENT OFFICE.

LESTER ALBERT PRATT AND JOHN H. CLARKE, OF WINCHESTER, MASSACHUSETTS,
ASSIGNORS TO MERRIMAC CHEMICAL COMPANY, OF WOBURN, MASSACHUSETTS,
A CORPORATION OF MASSACHUSETTS.

PROCESS FOR THE MANUFACTURE OF SODIUM SULPHIDE.

Application filed August 3, 1922. Serial No. 579,446.

To all whom it may concern:

Be it known that we, (1) LESTER ALBERT PRATT and (2) JOHN H. CLARKE, citizens of (1) the United States, (2) Canada, subject of King of Great Britain, residing at (1) Winchester, (2) Winchester, in the county of (1) Middlesex, (2) Middlesex, and State of (1) Massachusetts, (2) Massachusetts, have invented certain new and useful Improvements in Processes for the Manufacture of Sodium Sulphide, of which the following is a specification.

This invention relates to a process for the manufacture of sodium sulphide.

15 The principal object of the invention is to provide an economical and efficient process for the manufacture of sodium sulphide. Other objects of the invention, the accomplishment of which contribute to the accomplishment of the principal object are to provide a process in which the reaction conditions, particularly the temperature, are subject to easy and accurate control; the production of high yields of relatively 25 pure product; the use of inexpensive apparatus, that is, apparatus for which the combined original cost and maintenance cost is low as compared with the value of the product; economy of heat; small oxidation or secondary reaction losses; and small 30 losses by volatilization.

Other objects and advantages of the invention will be apparent from the following detailed description of the invention.

35 The process consists in flowing fused sodium sulphate (salt cake) or sodium acid sulphate (niter cake) mixed with finely divided carbonaceous material over or through a body or mass of highly heated inert material.

The process preferably is carried out in an electrically heated shaft furnace of either the resistance or induction type, but I contemplate the use of any other method 45 of heating which may be applied without contacting the furnace charge with air or products of combustion. For instance, a shaft furnace containing a filling of inert material through which the charge of salt cake or niter cake and carbonaceous ma-

terial is flowed may be heated by a flame or by contact with a hot body, such as a body of incandescent coke surrounding the shaft of the furnace. It is therefore to be understood that the invention is not limited to 55 electrical heating excepting as is required by the appended claims.

Apparatus suitable for carrying out the process is illustrated in the accompanying drawing in which the figure is a vertical 60 section of an induction electric furnace.

Referring to the drawing, 1 is the outer shell of the furnace formed of earthenware, brick or other suitable structural material which is a poor conductor of heat and 65 electricity. The shell 1 rests on a base 2 which may be made of concrete, said base 2 having a discharge opening 3 provided with a suitable closure represented by the slide 4. The upper end of shell 1 is closed 70 by a cover plate 5 having a charge opening 6 provided with a suitable closure represented by the slide 7. Extending between the charge opening 6 and the discharge 75 opening 3 is a cylindrical shaft formed of suitable non-conducting refractory material. As is illustrated the upper or pre-heating zone 8 is formed of magnesia brick; the central or reaction zone 9 is formed of carbon brick; and the lower or 80 drawing off zone 10 is formed of magnesia brick. The inner walls of the zone 10 of the shaft slope inwardly to the discharge opening 3. The space between the outer shell 1 and the shaft 8, 9, 10 is filled with 85 suitable material which is a heat insulator and a poor conductor of electricity.

Surrounding the shell 1 of the furnace in the region of the reaction zone 9 is a coil 90 of copper or other metallic pipe 11 the opposite ends of which are connected in an electric circuit. The coil 11 which forms the primary of the induction furnace is of sufficient size and comprises a sufficient 95 number of turns to provide the desired heating effect in the secondary of the furnace which comprises the furnace charge and the carbon brick walls of the reaction zone 9. The coil 11 is cooled by means of 100 water flowed through it as indicated.

The reaction zone 9 of the furnace contains a supporting and distributing filling 12 of some inert refractory material such as magnesia brick. The filling 12 may be made up of regular or irregular forms or fragments of inert material. In practice the units of the supporting and distributing filling preferably present sloping surfaces to the flowing charge. On the drawing the filling 12 is conventionally illustrated as checkerwork.

The process is carried out as follows: Electric current is supplied to the primary coil 11 sufficient to heat the reaction zone 9 of the furnace to a temperature of from 850° to 1100° C., and a mixture of carbonaceous material crushed to at least 20 mesh and ground salt cake or niter cake or a mixture of salt cake and niter cake is supplied to the furnace through the charge opening 6. The carbonaceous material employed in the charge preferably is free or nearly free from ash or other impurities. Petroleum coke is a satisfactory carbonaceous material. The proportions of carbonaceous material and salt cake or niter cake in the charge may vary. Good results are obtained by charging the furnace with a mixture of 12 parts by weight of salt cake with 5 parts by weight of petroleum coke. With this mixture and by maintaining a temperature in the reaction zone of the furnace between 850° and 950° C. a conversion of about 85 percent of the sodium sulphate to sodium sulphide is obtained and the furnace product contains from 75 to 85 percent of sodium sulphide.

The raw charge supplied to the furnace through the charge opening 6 is preheated in the zone 8 and arrives at the filling of inert material 12 in the reaction zone 9 in molten and fluent condition. The molten material flows in thin layers over the surfaces of the inert filling and due to the large surface exposure rapid conversion of the sulphate to sulphide takes place. The molten reaction product collects in the drawing off zone 10 and is withdrawn from time to time through the discharge opening 3.

50 Gases formed by the reaction of the sodium sulphate with the carbonaceous material escape from the furnace through a suitable gas outlet which is not illustrated on the drawing.

55 If crystallized sodium sulphide is desired the furnace product is discharged directly into water in quantity just sufficient to form a saturated solution of the sodium sulphide content of the furnace product. The bulk 60 of the unconverted sodium sulphate remains in the undissolved residue and after separation from the sodium sulphide solution is returned to the process. The sodium sulphide solution is separated from the undissolved residue by filtration or settling and

is cooled to crystallize the sodium sulphide which is separated and washed. The mother liquor and washings are then evaporated by the waste heat from the furnace for the recovery of their sodium sulphide content or the liquor and washings are used as a solvent for a further quantity of the furnace product.

The use of carbonaceous material which is free or nearly free from impurities, such as ash, as described above is desirable because such material does not introduce impurities into the product. Otherwise if impure carbonaceous material is used, such as coke from coal containing large amounts of ash, colloidal or gelatinous silicates of iron and aluminum will be formed when the furnace product is treated with water and interfere with the settling or filtration operation in the separation of the solution of sodium sulphide from the undissolved residue.

As is indicated above the sodium sulphate for the reaction is derived from either salt cake or niter cake or mixtures thereof and it is to be understood that these materials or any other sodium sulphate containing materials are included under the expression "sodium sulphate" in the appended claims.

We claim:

1. Process for the manufacture of sodium sulphide which comprises flowing a mixture of molten sodium sulphate with finely divided carbonaceous material in quantity sufficient to reduce the sulphate to sulphide through a supporting and distributing body of inert material at reacting temperature.

2. Process for the manufacture of sodium sulphide which comprises, mixing material containing sodium sulphate with finely divided carbonaceous material in quantity sufficient to reduce the sulphate to sulphide, melting the mixture, and flowing the melted mixture downwardly through a column of inert material at reacting temperature.

3. Process for the manufacture of sodium sulphide which comprises heating to reacting temperature a molten mixture of sodium sulphate with finely divided carbonaceous material in quantity sufficient to reduce the sulphate to sulphide in a thin layer in contact with inert material.

4. Process for the manufacture of sodium sulphide which comprises flowing a molten mixture of sodium sulphate with finely divided carbonaceous material in quantity sufficient to reduce the sulphate to sulphide over a supporting and distributing body of inert material at a temperature of from 850° to 1100° C.

5. Process for the manufacture of sodium sulphide which comprises, mixing about 12 parts of crushed salt cake with about 5 parts of pulverized petroleum coke, melting the mixture, and flowing the molten mixture downwardly through a column of inert ma-

terial heated to a temperature of from 850° to 950° C.

6. Process for the manufacture of sodium sulphide which comprises, flowing a molten mixture of sodium sulphate with finely divided carbonaceous material in quantity sufficient to reduce the sulphate to sulphide through a supporting and distributing body

of inert material, and passing electric current through the flowing molten mixture to 10 heat the same to reacting temperature.

In testimony whereof, we affix our signatures.

LESTER ALBERT PRATT.
JOHN H. CLARKE.
